MOUNT

Herman L. Seiden, Chicago, Ill.

Application August 20, 1952, Serial No. 21,124

Term of patent 14 years

(Cl. D61—1)

To all whom it may concern:

Be it known that I, Herman L. Seiden, a citizen of the United States of America, and a resident of Chicago, Cook County, Illinois, have invented a new, original, and ornamental Design for a Combined Light Bar and Camera Mount, of which the following is a specification, reference being had to the accompanying drawing, forming a part hereof.

Fig. 1 is a front elevational view of a combined light bar and camera mount showing my new design;

Fig. 2 is a top plan view of the same;

Fig. 3 is a rear elevational view of the same;

Fig. 4 is a side elevation of the same; and

Fig. 5 is a fragmentary side elevational view showing the side opposite Fig. 4.

I claim:

The ornamental design for a combined light bar and camera mount, as shown.

HERMAN L. SEIDEN.
